METHOD AND APPARATUS FOR STRINGING
TOBACCO LEAVES

Rush D. Touton, Wynnewood, Pa.

Application June 15, 1948, Serial No. 33,056

11 Claims. (Cl. 214—5.5)

1

This invention relates to an apparatus and method for stringing tobacco leaves.

As is well known, when tobacco is harvested, the leaves are strung on lengths of string secured at one end to a lath, the free end of the string is attached to the other end of the lath and the whole then racked up in a curing barn with the leaves hanging from the string for the curing of the tobacco leaves.

When the tobacco has cured, the laths are taken down, the ends of the string are cut free from the lath, the tobacco leaves pushed together and the balance of the string wound about the butt portions of the leaves and secured to form hands.

In practice heretofore, the stringing of the pairs of tobacco leaves has been accomplished manually by operators who string them by passing a needle, carried by the string at its free end, through the butts of the leaves. Such is open to a number of objections, chief among which is variation in the number of pairs of leaves per lath, unequal spacing of the pairs on the string, wide variation in the number of laths strung per day by different operators, which results in a limited average production, breakage of leaves due to inept operators, loss from falling leaves during curing resultant from improper stringing, difficulty in obtaining requisite labor for a short seasonable occupation and rising labor costs coupled with decreasing productivity.

As a consequence, there have heretofore been many efforts made to provide mechanism and procedure for the mechanical stringing of tobacco leaves which would give a constant number of pairs of leaves per lath, equal spacing of the pairs on the string and increased productivity per operator. Such efforts in the main have been directed toward the provision of mechanisms including a needle and adapted to accomplish the same type of stringing which is accomplished by manual operation. However, the results of such and other efforts have failed, for various reasons, in their purpose and the procedure involving manual stringing of the tobacco leaves has been continued despite its several well recognized disadvantages.

Now in accordance with this invention, a mechanism and method for the stringing of tobacco leaves is provided with at once economical and efficient operation, in that uniform spacing and number of leaves per lath is readily obtainable, the leaves are securely held by the string, with minimization of falling leaves, and the productivity of the operator is increased.

2

Generally speaking, the method according to this invention comprises the securing of leaves of tobacco at spaced intervals between a pair of strings, ends of which are secured together at an end of a lath, by successively crossing the strings over and under one another, or crossing one string about the other, between tobacco leaves, the butts of which are successively presented between the strings. More particularly, the strings are so arranged and manipulated that portions thereof will extend at rest for a period between crossings to enable successive tobacco leaves to be presented between them. The method in accordance with this invention broadly and in detail will be made more apparent from the following description of a form of apparatus embodying this invention and of its mode of operation.

Generally speaking, apparatus according to this invention will comprise rotating string carrying means, which, as will appear, may be continuously or intermittently rotated, in combination with means for guiding a pair of strings extending from the carrying means so that the strings in their extension beyond the guiding means will, in effect, be at rest throughout a large part of each 180° cycle of rotation of the carrying means in order to permit the insertion of the butts of tobacco leaves between the strings between crossings thereof.

In more detail, the apparatus may include means for effecting a temporary holding of the leaves on insertion between the strings before the crossing thereof.

Further, since the strings are held under tension, the butts of the leaves will, where they are engaged by the strings, be bruised or cut, which will promote the grip of the strings upon them and also promote the curing of the butt and stem portions of the leaves.

The apparatus according to this invention and its mode of operation according to the method of this invention will, in greater detail, be made apparent from the following description with reference to the accompanying drawings, in which:

Figure 1 is a side view, partly broken away, of an apparatus embodying this invention.

Figure 2 is a top view of the apparatus shown in Figure 1.

Figure 3 is a rear view of the apparatus shown in Figure 1.

Figure 4 is a fragmentary view, partly broken away, showing details of construction of the apparatus shown in Figure 1.

Figures 5, 6 and 7 are fragmentary views show-

ing details of construction of the apparatus shown in Figure 1.

Figures 8 and 9, respectively a plan and a side view, show details of construction of the apparatus shown in Figure 1 and, at the same time, show pairs of tobacco leaves secured by the strings.

Figure 10 shows a detail of construction of the apparatus of Figure 1.

Figure 11 shows a detail of construction of the apparatus of Figure 1.

In the several figures variously 1 indicates a framework in the rear end of which is slidably mounted a motor 2 in unit with a speed reduction gear 3. The driving shaft 4 from the reduction gear is equipped with an adjustable pitch sheave or pulley 5, of well known construction, for the reception of a V belt 6. The V belt 6 is engaged with a pulley on a shaft 7 mounted in the framework 1.

The shaft 7 carries on its forward end a disc 8 on the rear face of which are mounted a pair of receptacles 9, each containing a length or spool of string 10. The receptacles 9 are desirably secured to the disc 8 in opposite relation or 180° apart.

Adjacent to the receptacles 9, respectively, the disc 8 carries string guides 11, through which the strings 10 are led to tension devices carried by the disc and from which they pass through holes 12 formed 180° apart in the disc adjacent to its periphery.

The tension devices may be of any desired type. However, as illustrated, they may each comprise a pair of discs 13 mounted on a shaft carried by a bracket 14, secured to disc 8 and between which the strings 10 pass to adjustable spring 15, which acts to press the discs together to put tension on the strings. The tension on the strings 10 may be released through the medium of levers 16 carried by a sleeve 17 on shaft 7 and pivoted on brackets 14, one arm of each of which 16' engages between the springs 15 and the discs 13. The sleeve 17 is advanced to cause the arms 16 to release the tension of springs 15 on the discs 13 by a cam member 18 embracing shaft 7 adapted to work against a stop 19 on shaft 7. The cam member is carried on the end of a rod 20 connected to a foot treadle 21. The cam member 18 is normally held inoperative by a spring 22 connected to the framework 1 and to the foot treadle 21. When the foot treadle is depressed the cam 18 will advise sleeve 17, which will cause the arms 16' of levers 16 to compress spring 15 away from the discs 13.

It will be appreciated that disc 8 serves as a rotatable support for the spools of string and may as well have various forms other than a disc. Thus, in place of the disc 8 a skeleton structure, as, for example, a pair of crossed members, could be used.

Spaced forwardly of the disc 8 is a fixed plate 23, provided with a transverse slot 24 of a length substantially less than the diameter of the disc 8 and of a width sufficient for free passage of the strings 10. The slot 24 may be a straight slot, as shown in Figure 4. However, desirably it will be oppositely recessed at its ends as shown at 25, Figure 7.

As illustrative, for example, the disc 8 may have a diameter of about 12 inches and the slot may have a length of about 3 inches and a width of about 0.20 inch. If the opposite recesses 25 be formed at the ends of the slots, they may have a depth of about 0.10 inch.

Extending forwardly from the plate 23 and spaced below the slot 24 is a pair of spring arms 26. The rear ends of the arms 26 are secured to the plate beyond the ends of slot 24 and, extending toward each other, terminate in upturned end portions 26' extending to points above the plane of the slot 24 and spaced apart a distance less than the combined thickness of the butts of a pair of average tobacco leaves, of the type to be strung, when placed face to face. Cutting elements or knives 27 extend in opposite staggered relation from the upturned end portions 26' of the spring arms 26 at points spaced above the plane of the slot 24.

Extending forwardly from the plate 23 and spaced above the plane of the slot 24 is a horizontal plate 28 of a width about equal to, or somewhat greater than, the length of slot 24. The plate 28 extends to a point above, or somewhat beyond, the upward ends 26' of the spring arms 26.

A shield 50 of conical shape will extend rearwardly from plate 23 to disc 8, as shown in Figures 1 and 2.

Driven from the shaft 7, by means of a V belt 29 and suitable pulleys, is a shaft 30, mounted in the framework 1, and which in turn, through gearing 31, drives a transversely extending shaft 32 mounted in the framework above and forwardly of the forward end of plate 23. The shaft 32 carries a sprocket 33, which serves to drive a chain 34, which engages a sprocket 35 carried by a shaft 36 mounted in the forward end of the framework 1.

The chain 34 carries a pair of hooks 37 and to the rear of each hook, considering the chain to be traveling in the direction indicated by the arrow Figure 1, the chain carries a series of spaced angle members 38. As shown, each of the series of angle members 38 comprises twenty members. However, as will be seen, the precise number of members is of no primary significance.

The motor 2 will be supplied with current from any suitable source through a rheostat 39 supported in the framework 1 at a point above the plates 28 and controlled by a finger 40 having a flat portion extending forwardly of the plate 28 and in line with the space between the upturned end portions 26' of the spring arms 26.

The finger 40 will normally drop below the under surface of plate 28 in which position of the finger the motor will be stopped or its speed will be relatively slowed as the rheostat is set to stop or merely slow the motor. However, the finger 40 may be raised, as will appear, to the plane of the undersurface of the plate 28, in which position the motor will start, or its speed will be increased as the rheostat is set.

For the operation of the apparatus described above, strings 10, which will be of any usual or desired type for the stringing of tobacco leaves, are led from the lengths or spools in the receptacles 9, through guides 11, over the tension devices, the tension being released by depression of foot treadle 21, through holes 12 in disc 8, through slot 24 in plate 23, beneath plate 28 and between the upturned end portions 26' of arms 26.

The chain 34 is adjusted so that one of the hooks 37 will be positioned just ahead of the forward end of the rheostat finger 40.

The ends of the strings 10 are then pulled out and secured together to the end of a lath A, for example, as is usual, by turning them about the end portion of the lath and passing through a slot formed in the end of the lath. The foot

treadle 21 is released to put tension on the strings and the strings adjacent the lath are then laid over the hook 37 with the lath hanging from the hook.

Tobacco leaves B, to be strung, are laid on a table C beneath the apparatus in oppositely extending piles with the butts adjacent, as shown in Figure 1 and the operator takes position in front of the table.

The motor 2 is started and the rheostat, for example, being set for speed control, will operate at a relatively slow speed, since the rheostat control finger 40 will be in its lower position, as shown in Figure 1. With starting of the motor 2, the chain 34 will be driven, in the direction of the arrow Figure 1, the hook 37 carrying the lath A will advance and the strings 10 will be drawn out through slot 24 in plate 23 and between the upturned end portions 26' of spring arms 26. At the same time the disc 8 will be rotated.

During the greater part of each 180° rotation of disc 8, the strings 10, while having a continuous forward motion, due to the travel of hook 37, will lie in a substantially horizontal plane, while extending from the ends of slot 24 in plate 23 between the upturned end portions 26' of spring arms 26, and then will quickly cross over as the spools approach reversal of the positions. Here it will be noted that while the strings 10 ahead of plate 23 will have a continuous relative rotary motion due to the continuous rotation of disc 8, the slot 24 in plate 23, which is of a length less and of a width greatly less than the diameter of disc 8, will act to give them an intermittent rotary motion beyond plate 23, since during a large part of each 180° revolution of disc 8 the strings will lie at the ends of the slot. Where the slot is provided with recesses 25 at its ends, the period during which the strings will lie in a plane will be increased, since the recesses will prevent the strings from creeping as the point of crossover is approached. Thus, it will be noted that while the supplies from which string 10 are drawn are continuously relatively rotated by the disc 8, the slot 24, which the apparatus is operating with continuous rotation of disc 8, acts to dampen their relative rotary motion and convert it to an intermittent relative rotary motion in their extension beyond plate 23.

Now, while in the rotation of disc 8 the strings 10 lie in a plane, the operator, having placed the butts of a pair of the tobacco leaves B together, inserts the pair of butts, with the leaves edgewise, upwardly between the spring arms 26 and the strings 10 until the ends of the butts contact the underside of plate 28 and then moves the butts forwardly between the end portions 26' of the spring arms 26, which separate to permit the butts to pass and then spring back to normal position. As the butts pass between the end portions 26', the knives form slits in them.

The end portions 26' serve to constrict the strings about the butts sufficiently to initially hold them until, in the rotation of disc 8, the strings are crossed one over the other, which causes the butts to be firmly gripped or held by the strings, having in mind that the strings are under tension.

Further, with use of relatively thin string the butts of the leaves where engaged by the strings, will be indented or slightly cut, which will promote the grip of the strings on the butts and also will promote the curing of the butts and stems of the leaves in the curing operation.

When the butts of a pair of leaves have been

positioned so that they are initially held by the strings 10, as described above, the ends of the butts will serve to lift the rheostat control finger 40 to increase the speed of the motor 2 to standard. The operator assembles successive pairs of leaves, using both hands and repeats the operation of engaging the butts as the strings periodically lie in a plane for successive periods of time between crossings in the continued rotation of the disc.

The angle members 38, carried by chain 34, in number equal to the number of pairs of leaves to be strung on a lath, serve as spacers for the pairs of leaves.

The operation as described above will continue, with the motor at standard speed, until the required number of pairs of leaves for a lath have been strung, unless the operator fails to present the butts of a pair of leaves in time, considering the forward motion of the strings for proper spacing with respect to the preceding pair when the strings are crossed over. In such event, the rheostat control finger, which is of proper length with respect to the desired spacing of the pairs, will be released by the butts of the preceding pair and will drop, slowing the motor 2, and consequently the crossing over of the strings, until raised again by engagement with the delayed succeeding pair, thus allowing the operator to catch up, with avoidance of irregular spacing of the pairs and insurance that the requisite number of pairs are strung on the lath.

As the hook 37 carrying the lath A advances, it will engage the bracket 45, which, in the further advance of the lath, will lift its free end so that it will be in a position convenient to the operator when the number of pairs of leaves to be strung on the lath has been engaged by the crossing of the strings.

When the number of pairs for the lath, usually twenty, have been engaged by the strings, or "strung," the operator, with the motor 2 in operation, grasps the free end of the lath with one hand and the strings behind the last pair of leaves with the other, at the same time releasing the tension on the strings by depressing the foot treadle 21. While maintaining tension on the strings with respect to the end of the lath to which they are secured, in order to maintain their hold on the butts of the pairs, the operator severs the strings, by means of any conveniently located fixed knife, and secures the ends, with the strings under tension, to the free end of the lath, as by twisting about the lath and passing through a slot in its end. The lath with the strung pairs will then be removed for racking by lifting the strings from the hook 37.

When the rheostat 39 has been set to stop the motor 2, as compared with slowing it or reducing its speed when the finger 40 is in lowered position, the operation will be as described above, except that the motor 2 will stop between the insertion of successive pairs of leaves, the finger 40 dropping as a pair of leaves leave it in their advance and be raised to restart the motor on the insertion by the operator of the next pair of leaves. Thus, the operation of the machine and the rotation of disc 8 carrying lengths of string may be continuous or intermittent.

When the strung lath has been removed, the free ends of the strings 10 are secured to an end of a fresh lath and hung on the succeeding hook 37 as it reaches a position just beyond the end of rheostat control finger 40. The operation of

stringing as described above will then be repeated.

During the operation of securing the strung pairs to the lath and removing the strung lath and placing a fresh lath, the motor 2 will be slowed or stopped as the rheostat is set to allow the operator to remove and replace the laths by the dropping of rheostat control finger 40 and will be brought up to standard speed again, or started, upon the initial engagement with the strings of the butts of the first pair of leaves to be strung on the fresh lath.

When the tobacco leaves, strung as described, have been cured, they will be readily removed from the lath by laying them flat on a table, severing the strings at the ends of the lath, which will relieve the tension on them, sliding the pairs together and tying into a bunch with the strings. Alternatively, one or both of the strings may readily be pulled out and the pairs of leaves bunched and held in any desired manner.

It will be appreciated that the speeds of motor 2 under control of the rheostat 39 and the speed of the drive through the adjustable pitch sheave 5 will be selected with respect to the skill of the operator where the rheostat acts to slow rather than stop the motor.

In the above description of apparatus and procedure reference is made to the stringing of tobacco leaves in pairs. However, it will be understood that such is intended to be illustrative and not limiting, it being apparent that single leaves, or groups, or bunches comprising more than two leaves may be strung as may be desired.

From the above description, it will be noted that the tobacco leaves are secured by crossing of the strings relative to one another, the strings being preferably crossed alternately over and under the other, thus forming self-adjusting cradles. The strings thus alternately support each other. The under string supports the over string and as the under string rises to cross over the companion string, it rises alongside the butt of the tobacco leaf to support it. The over string acts to tension the under string and equalize the load and as the over string descends to become the under string, the companion under string is rising to become the over string.

It will be understood that various modification may be made in the apparatus and procedure described above without departing from this invention, it being understood that while various detail of apparatus and procedure described forms a part of this invention, such is not contemplated as in any wise limiting upon the broad aspects of the invention from either the apparatus or method standpoints.

What I claim and desire to protect by Letters Patent is:

1. Apparatus for stringing tobacco leaves which comprises rotatable means rotatable about an axis, means for supporting a pair of strings in oppositely spaced relation relative to the axis of said rotatable means, means for holding together free ends of said pair of strings led from said rotatable means, tension means carried by said rotatable means for maintaining tension on said pair of strings in their extension from said rotatable means to said holding means, means for continuously rotating said rotatable means and for simultaneously imparting a forward movement to said holding means and means positioned between said rotatable means and said holding means for continuously maintaining said pair of strings in substantially a single plane.

2. Apparatus for stringing tobacco leaves which comprises a support rotatable about an axis, means for securing a pair of lengths of string to said support, means on said support for leading a pair of strings from said support oppositely spaced with relation to the axis of said support, an endless traveler spaced from and extending forwardly of said support, holding means on said traveler to engage the free ends of a pair of strings led from said support, tension means carried by said support for maintaining tension on a pair of strings in their extension from said support to said traveler and a stationary member positioned between said support and said holding means and provided with a slot for the passage of a pair of strings extending from said support to said holding means, said slot continuously maintaining said pair of strings in substantially a single plane.

3. Apparatus for stringing tobacco leaves which comprises a support rotatable about an axis, means for securing a pair of lengths of string to said support, means on said support for leading a pair of strings from said support oppositely spaced with relation to the axis of said support, an endless traveler spaced from and extending forwardly of said support, holding means on said traveler to engage the free ends of a pair of strings led from said support, tension means carried by said support for maintaining tension on a pair of strings in their extension from said support to said traveler and a stationary member positioned between said support and said holding means and provided with a substantially horizontal slot for the passage of a pair of strings extending from said support to said holding means, said horizontal slot continuously maintaining said pair of strings in a substantially horizontal plane.

4. Apparatus for stringing tobacco leaves which comprises a support rotatable about an axis, means for securing a pair of lengths of string to said support, means on said support for leading a pair of strings from said support oppositely spaced with relation to the axis of said support, an endless traveler spaced from and extending forwardly of said support, holding means on said traveler to engage the free ends of a pair of strings led from said support, tension means carried by said support for maintaining tension on a pair of strings in their extension from said support to said traveler and a stationary member positioned between said support and said holding means and provided with a substantially horizontal slot for the passage of a pair of strings extending from said support to said holding means, said slot having a width less than the distance between the means for leading a pair of strings from said support and continuously maintaining said pair of strings in a substantially horizontal plane.

5. Apparatus for stringing tobacco leaves which comprises a support rotatable about an axis, means for securing a pair of lengths of string to said support, means on said support for leading a pair of strings from said support oppositely spaced with relation to the axis of said support, an endless traveler spaced from and extending forwardly of said support, holding means on said traveler to engage the free ends of a pair of strings led from said support, tension means carried by said support for maintaining tension on a pair of strings in their extension from said support to said traveler, a stationary member positioned between said support and said holding

means and provided with a substantially horizontal slot for the passage of a pair of strings extending from said support to said holding means, said horizontal slot continuously maintaining said pair of strings in a substantially horizontal plane and a pair of resilient members extending forwardly from said slotted member and having end portions spaced apart a distance less than the length of said slot and positioned for the passage therebetween of a pair of strings in extension from said slot to said holding means.

6. Apparatus for stringing tobacco leaves which comprises a support rotatable about an axis, means for securing a pair of lengths of string to said support, means on said support for leading a pair of strings from said support oppositely spaced with relation to the axis of said support, an endless traveler spaced from and extending forwardly of said support, holding means on said traveler to engage the free ends of a pair of strings led from said support, tension means carried by said support for maintaining tension on a pair of strings in their extension from said support to said traveler and a stationary member positioned between said support and said holding means and provided with a substantially horizontal slot for the passage of a pair of strings extending from said support to said holding means, said horizontal slot continuously maintaining said pair of strings in a substantially horizontal plane, a prime mover for rotating said support and driving said traveler and means for controlling operation of said prime mover positioned adjacent to said slotted member and adjacent to the path of travel of a pair of strings in extension from the slot in said member.

7. Apparatus for stringing tobacco leaves which comprises a support rotatable about an axis, means for securing a pair of lengths of string to said support, means on said support for leading a pair of strings from said support oppositely spaced with relation to the axis of said support, an endless traveler spaced from and extending forwardly of said support, holding means on said traveler to engage the free ends of a pair of strings led from said support, tension means carried by said support for maintaining tension on a pair of strings in their extension from said support to said traveler, a stationary member positioned between said support and said holding means and provided with a substantially horizontal slot for the passage of a pair of strings extending from said support to said holding means, said horizontal slot continuously maintaining said pair of strings in a substantially horizontal plane and a pair of resilient members extending forwardly from said slotted member and having end portions spaced apart a distance less than the length of said slot and positioned for the passage therebetween of a pair of strings in extension from said slot to said holding means.

8. The method of stringing tobacco leaves which comprises securing a pair of strings by one end of each string to the end of a lath, continuously advancing the strings and the lath longitudinally while maintaining said strings under tension, maintaining a substantially fixed distance between the strings in a substantially vertical plane remote from the secured ends of the strings, continuously rotating said strings in one direction in said vertical plane about a point intermediate the strings as the strings are advanced through said vertical plane, confining the lateral movement of the strings at a point intermediate said vertical plane and the secured ends

of the strings in order to give the strings an intermittent lateral movement, presenting the butts of tobacco leaves successively between said strings immediately behind their point of convergence and between the periods of their intermittent lateral movement, severing the strings and while maintaining tension thereon securing the strings to the opposite end of the lath.

9. The method of stringing tobacco leaves which comprises securing a pair of strings by one end of each string to the end of a lath, continuously advancing the strings and the lath longitudinally while maintaining said strings under tension, maintaining a substantially fixed distance between the strings in a substantially vertical plane remote from the secured ends of the strings, continuously rotating said strings in one direction in said vertical plane about a point intermediate the strings as the strings are advanced through said vertical plane, confining the lateral and vertical movement of the strings at a point intermediate said vertical plane and the secured ends of the strings, said lateral movement being substantially less than the distance between the strings in said vertical plane in order to give the strings an intermittent lateral movement, presenting the butts of tobacco leaves successively between said strings immediately behind their point of convergence and between the periods of their intermittent lateral movement, severing the strings and while maintaining tension thereon securing the strings to the opposite end of the lath.

10. The method of stringing tobacco leaves which comprises securing a pair of strings by one end of each string to the end of a lath, continuously advancing the strings and the lath longitudinally while maintaining said strings under tension, maintaining a substantially fixed distance between the strings in a substantially vertical plane remote from the secured ends of the strings, continuously rotating said strings in one direction in said vertical plane about a point intermediate the strings as the strings are advanced through said vertical plane, confining the lateral and vertical movement of the strings at a point intermediate said vertical plane and the secured ends of the strings in order to give the strings an intermittent movement in a substantially horizontal plane, said lateral movement being substantially less than the distance at the point of confinement between straight lines joining the points where said strings are secured and the points where they pass through said vertical plane respectively, presenting the butts of tobacco leaves successively between said strings immediately behind their point of convergence and between the periods of their intermittent lateral movement, severing the strings and while maintaining tension thereon securing the strings to the opposite end of the lath.

11. The method of stringing tobacco leaves which comprises securing a pair of strings by one end of each string to the end of a lath, continuously advancing the strings and the lath longitudinally while maintaining said strings under tension, maintaining a substantially fixed distance between the strings in a substantially vertical plane remote from the secured ends of the strings, continuously rotating said strings in one direction in said vertical plane about a point intermediate the strings as the strings are advanced through said vertical plane, confining the lateral and vertical movement of the strings at a point intermediate said vertical plane and the

11

secured ends of the strings in order to give the strings intermittent horizontal motion, the permitted lateral movement being a distance less than the fixed distance maintained between the strings in said first vertical plane, the permitted vertical movement being slightly in excess of twice the diameter of the strings, presenting the butts of tobacco leaves successively between said strings immediately behind their point of convergence and between the periods of their intermittent lateral movement, severing the strings and while maintaining tension thereon securing the strings to the opposite ends of the lath.
